UNITED STATES PATENT OFFICE.

OSCAR L. VANCE, OF DECATUR, INDIANA.

LOCK.

1,201,993.

Specification of Letters Patent. Patented Oct. 17, 1916.

Application filed April 19, 1916. Serial No. 92,139.

To all whom it may concern:

Be it known that I, OSCAR L. VANCE, a citizen of the United States, and a resident of Decatur, in the county of Adams and State of Indiana, have invented a certain new and useful Improvement in Locks, of which the following is a specification.

My present invention relates generally to locks and more particularly to a lock of the permutation type, adapted for general application in the uses to which locks are adapted, and particularly useful for locking the operating parts of an automobile in either operative or inoperative condition.

The preferred construction of my invention, applicable as it is to various uses as hereinafter shown, will be better understood by reference to the following description, in connection with the accompanying drawings forming a part of this specification, and in which—

Figure 1 is a perspective view of my improved lock with connections for using the same in an automobile. Fig. 2 is a vertical longitudinal section through the lock. Fig. 3 is a cross section taken substantially on line 3—3 of Fig. 2. Fig. 4 is a perspective view illustrating certain parts of the lock in detached relation. Fig. 5 is a view partly in elevation and partly in section, illustrating a modified mounting for the lock in connection with the dash of an automobile. Fig. 6 is a sectional view illustrating application of the lock as a mortise lock for doors, etc. Fig. 7 is a detail perspective view of the inner end of the shaft, constructed for use as in Fig. 6. Fig. 8 is a view, partly in elevation and partly broken away and in section, illustrating its use as an outside door lock, and Fig. 9 is a view similar to Fig. 7 for use in connection with Fig. 8.

Referring now to these figures, the lock as proposed by my invention, and in each instance of its use, includes a cylindrical shaft 10 having lateral extensions 11 projecting in diametrically opposite directions from its outer end and forming a handle, and provided with an inner reduced portion 12 forming an annular shoulder 13 intermediate its ends and against which shoulder abuts a washer 14 mounted on the reduced portion 12. The shaft 10 is also provided with a longitudinally extending key slot 15 projecting substantially from its han-

dle at the outer end thereof, to a point adjacent the inner end, for the reception of a key 16 having an outer angular projection 17 forming a finger-piece adjacent the handle 11 of the shaft, and having an inner angular locking end 18. This key 16 is also provided at a point intermediate its ends with serrations or teeth 19 forming notches between them in which are seated the inner beveled edges 20 of permutation disks 21, 22, and 23, surrounding the central opening 24 of said disks which receive the reduced portion 12 of the shaft 10.

The disks 21, 22, and 23 are each also provided with a slot 25 at one point in its inner beveled edge 20, so that when the slots of the several disks are alined with the key 16, the latter may be moved lengthwise in the shaft groove 15, to and away from locked position.

The reduced portion 12 of the shaft extends through the central opening of the lock plate 26 having a hub portion 27 provided at one face with recesses 28 and 29 at an angle of 90° with respect to one another, and each of which is adapted for the reception of the inner angular locking end 18 of the key 16, it being noted that the several permutation disks 21, 22, and 23, before mentioned, are of progressively increasing diameter and arranged between the lock plate 26 and the washer 14, so as to maintain the series of disks in position for ready adjustment in use. Each of the said disks is provided in its rear face with slots 30 diametrically opposite one another, and for the reception of bent extensions 31 of substantially concavo-convex spring plates 32 bearing against the front faces of the next rearmost disks of the series and the front face of the lock plate 26, so as to hold the several disks of the series against rattling in use and accidental displacement.

Thus, when the slots 25 of the several permutation disks are alined with the key 16, as shown in Fig. 2, the key may be thrust inwardly in the direction of its length and in order to move its inner locking end 18 out of engagement with the recess 28 or the recess 29, and thus free the shaft 10 for rotation by manipulation of the handle 11, to insert or withdraw a locking bolt of a door or other structure, or open or close a valve and the like through suitable connections for this purpose.

110

- As used in connection with a mortise door lock, as seen in Figs. 6 and 7, the inner end of the shaft 10 is provided with an angular extension 33 pivotally connected to one end 5 of an arcuate bolt 34, so that rotation of the shaft 10 in opposite directions, serves to insert the bolt within and withdraw the same from its keeper 35, dependent upon the direction of such rotation.
- 10 As shown in Figs. 8 and 9, in connection with an ordinary outside lock, the inner end of the shaft 10 may be provided with an angular extension 36, directly movable upon rotation of the shaft into and out of its 15 keeper 37.

As shown in Figs. 1 and 2, however, the shaft 10, adapted in this instance, for the control of a fuel valve 38 within a fuel pipe 39, is connected to the valve by means of a 20 flexible shaft (not shown) incased within a flexible casing 40, so that, upon leaving the automobile for any length of time, the operator may close and lock the valve 38 and thus prevent unwarranted use or manipulation 25 of the car during his absence therefrom. In the latter instance, the inner end of the shaft 10 may also extend through a casing 41 and is, in this instance as well as other instances, provided with an annular groove 30 42 engaged by a conformable opening in the rear plate 43 of the casing, whereby to form a bearing for the shaft and eliminate longitudinal movement and rattling thereof, the plate 43 just mentioned being for this purpose 35 in two parts, as seen in Fig. 1.

The casing 41 may be secured through an opening in the dash, indicated in dotted lines at 44 in Fig. 2, or may be extended within an angular tubular support 45 in turn attached to the dash 46, as shown in Fig. 5. In either instance, the casing 41 may have a pair of internal spring contact fingers 47 and 48 as most plainly seen in Fig. 3, the inner free ends of which are in movable contact 40 with a portion of the inner surface of the shaft 10, and the latter may, at this point, be provided with an insulated surface 49 in which is embedded a contact plate 50. The ignition wires 51 and 52, as seen in Fig. 50 1, are led into the casing 41 and respectively connected to the contact fingers 47 and 48, so that, when the shaft 10 is turned and locking extension 18 of key 16 engaged within lock plate recess 28, as shown in Fig. 3, the ignition circuit will be completed, while, when the shaft is turned to engage and lock extension 18 within recess 29, the contact plate 50 will be moved away from the contact finger 48 and the circuit thus broken.

60 Rotative movements of the shaft 10 are limited to the movement of the locking extension 18 between pins 53 and 54 projecting inwardly from the hub portion 27 of lock plate 26, so that, in the event of the use 65 of the electrical controlling connections just

above described, interference of the extension 18 with the contact fingers 47 and 48 is prevented.

It is obvious, therefore, that a lock as constructed in accordance with my invention, is 70 simple, comparatively inexpensive, strong, and durable, viewed in the light of other locks of the type, and is, in addition, capable of application to a great variety of uses in connection with which locks of this type are 75 generally put, and arranged and adapted to be used in connection with various devices and locks now controlled and actuated by keys.

I claim:

1. In a lock of the character described, the combination of a rotatable shaft having a handle at its outer end and having a reduced inner portion, forming an intermediate annular shoulder, a washer disposed against 85 said shoulder, a rigid lock plate through which the inner end of the shaft extends, having recesses in its inner face, said shaft being provided with a longitudinally extending slot, a locking key slidable in said slot and having an angular finger piece adjacent the handle of the shaft, and an inner angular locking end for engagement within the locking recesses of the lock plate, said key having serrations intermediate its ends 90 forming notches therebetween, a series of permutation disks surrounding the shaft and disposed between the said lock plate and the said washer, each of said disks having a beveled edge surrounding its central opening receiving the shaft to interfit one of the notches of the locking key and having a slot in its said edge through which the key may be moved in the direction of its length when aligned therewith.

2. In a lock of the character described, the combination of a rotatable shaft having a handle at its outer end and having a reduced inner portion forming an intermediate annular shoulder, a washer disposed against 105 said shoulder, a rigid lock plate through which the inner end of the shaft extends, having recesses in its inner face, said shaft being provided with a longitudinally extending key slot, a locking key slidable in said slot and having an angular finger piece adjacent the handle of the shaft and an inner angular locking end for engagement within the locking recesses of the lock plate, said key having serrations intermediate its ends 110 forming notches therebetween, a series of permutation disks surrounding the shaft and disposed between the said lock plate and the said washer, each of said disks having a beveled edge surrounding its central opening receiving the shaft to interfit one of the notches of the locking key and having a slot in its said edge through which the key may be moved in the direction of its length when aligned therewith, each of said disks being 115 120 125 130

- provided in its rear face with recesses, and a spring plate having bent extensions engaged in the said recesses and bearing against the next adjacent disk and the adjacent face of the lock plate whereby to hold the several disks against accidental displacement and rattling.
3. In a lock of the type described, the combination of a rotatable shaft, a rigid lock plate through which the shaft is extended, having locking recesses radiating from the central portion thereof around the shaft, a longitudinally movable locking key rotatable with the said shaft and having an angular inner end movable into and out of the locking recesses of the lock plate, upon longitudinal movement of the key, said key being provided with intermediate notches, permutation disks mounted on the shaft and interfitting the notches of the key to prevent longitudinal movement thereof, each of said disks being provided with a slot through which the key is movable in the direction of its length, when alined therewith.
4. In a lock of the type described, the combination of a rotatable shaft, a rigid lock plate through which the shaft is extended, having locking recesses radiating from the central portion thereof around the shaft, a longitudinally movable locking key rotatable with the said shaft and having an angular inner end movable into and out of the locking recesses of the lock plate, upon longitudinal movement of the key, said key being provided with intermediate notches, permutation disks mounted on the shaft and interfitting the notches of the key, each of said disks being provided with a slot through which the key is movable in the direction of its length when alined therewith, said shaft having a longitudinal groove in which the said locking key works and being provided with a handle adjacent its outer end.
5. In a lock of the type described, the combination of a rotatable shaft, a rigid lock plate through which the shaft is extended, having locking recesses radiating from the central portion thereof around the shaft, a longitudinally movable locking key rotatable with the said shaft and having an angular inner end movable into and out of the locking recesses of the lock plate, upon longitudinal movement of the key, said key being provided with intermediate notches, permutation disks mounted on the shaft and

interfitting the notches of the key, each of said disks being provided with a slot through which the key is movable in the direction of its length when alined therewith, said shaft having a handle at its outer end and said key having an angular finger piece adjacent the handle of the shaft whereby it may be moved longitudinally with respect to the shaft.

6. In a lock of the type described, the combination of a rotatable shaft, a rigid lock plate through which the shaft is extended, having locking recesses radiating from the central portion thereof around the shaft, a longitudinally movable locking key rotatable with the said shaft and having an angular inner end movable into and out of the locking recesses of the lock plate, upon longitudinal movement of the key, said key being provided with intermediate notches, permutation disks mounted on the shaft and interfitting the notches of the key, each of said disks being provided with a slot through which the key is movable in the direction of its length when alined therewith, and means for preventing longitudinal movement of the said shaft.

7. In a lock of the type described, the combination of a rigid lock plate, a shaft rotatable therethrough, having a handle at its outer end and held against longitudinal movement, means rotatable with the shaft and movable longitudinally of said shaft into and out of engagement with the said lock plate, for normally holding the shaft against rotative movement, and permutation disks mounted on the shaft and normally preventing longitudinal movement of said locking means, said disks having slots through which said locking means may move longitudinally when alined therewith.

8. In a lock of the character described, a rigid lock plate, a shaft rotatable therethrough and having a longitudinal groove, a key slideable in said groove into and out of locking engagement with a portion of the said lock plate and normally preventing rotative movement of the shaft, permutation disks mounted on the shaft and normally engaging said key to prevent sliding movement thereof, each of said disks having a slot through which the key is movable when alined therewith.

OSCAR L. VANCE.
